UNITED STATES PATENT OFFICE.

ALWIN J. SCHEUER, OF NEW YORK, N. Y.

BILL-FOLD.

1,185,723.

Specification of Letters Patent. Patented June 6, 1916.

Application filed September 16, 1914. Serial No. 861,942.

To all whom it may concern:

Be it known that I, ALWIN J. SCHEUER, a citizen of the United States, residing in the city, county, and State of New York, have 5 invented certain new and useful Improvements in Bill-Folds, of which the following is a specification.

The invention is an improvement in bill 10 folds, and has for its object to facilitate the insertion of bills and their inspection when in the bill pocket, and also to increase the safety of such pocket-books. This is accomplished by means of a gullet or vent, which is formed in one wall of the pocket 15 and covered by a special flap, as hereinafter more particularly set forth.

In the drawings illustrating the preferred embodiment of the invention: Figure 1 is an inside view of the bill fold spread out, 20 with the special flap thrown back revealing the corner of a bill in the pocket; and Fig. 2 is a fragmentary view showing the left-hand section of the bill fold with the flap closed.

25 The bill fold comprises a full length bill pocket, closed at the ends and along the bottom and open at the top, and is preferably of the three fold type, comprising sections 1, 2 and 3, which fold upon each other 30 transversely at the regions designated 4 and 5. The sections 2 and 3 may bear card pockets 6 and 7 upon their inner faces.

The inner wall 8 of the end section 1 is formed with a gullet 9, extending from its 35 upper, free edge inward for a substantial distance, and of a suitable width to expose the numeral bearing corner of a bill, as indicated in Fig. 1. In form it may be approximately as wide as its section at the top 40 and taper toward the bottom. The gullet is adapted to be covered by a flap 10, which is secured to the outer wall 11 of the bill pocket so as to fold over the cut-away portion of the inner wall, to which it may be 45 fastened by snap-fastener elements 12 and 13, below the gullet. This flap is local to the section 1 and does not close the remainder of the mouth of the bill pocket, its width being such as to cover the gullet

and somewhat less than the width of the 50 section.

In use the gullet or vent renders it easy to insert bills, even if old and lacking in stiffness, since the pocket may be opened much wider than is the case with ordinary bill 55 folds, and the tendency of the walls at the lower corners to hug each other when the top is drawn open is overcome. By opening the flap as shown in Fig. 1, the corner of the topmost bill is exposed, and it is readily possible by turning over the corners to count the bills or to ascertain the denominations of those beneath. The flap fastened over a portion of the mouth of the pocket affords additional security, yet permits the ready removal of bills, since the inner wall of the pocket to the right of the vent may be pulled wide open even with the flap closed, thus affording an adequate opening through which the contents may be extracted. 70

What I claim as new is:

1. A bill fold, comprising a full length foldable bill pocket, said pocket being closed at one long side and at the short sides and having its mouth at the other long side and 75 being provided in one wall with a gullet, which gullet extends transversely inward from the mouth of the pocket, and a flap to cover the gullet.

2. A pocket-book having a full length bill 80 pocket and comprising sections foldable transversely upon each other, said pocket being closed at one long side and at the short sides and having its mouth at the other long side, one of said sections having a vent 85 in the inner wall of the bill pocket extending inward from the said mouth adjacent one end of the pocket-book, and a flap local to said section for covering the vent.

3. A bill fold comprising a full length 90 foldable bill pocket provided in its inner wall adjacent one end with a gullet, in combination with a flap on the outer wall to cover said gullet and means for fastening the flap to the inner wall, said flap closing 95 only the end portion of the mouth of the pocket and leaving the remainder thereof open.

4. A bill fold comprising a full length bill pocket comprising outer and inner walls united at one long side and the two short sides and having its mouth at the remaining long side, the said inner wall being provided with a gullet extending inward from the mouth, and a flap united with the free edge of the outer wall to cover said gullet.

Copies of this patent may be obtained for five cents each, by addressing the "Commissioner of Patents, Washington, D. C."

In testimony whereof, I have signed this specification in the presence of two witnesses.

ALWIN J. SCHEUER.
